UNITED STATES PATENT OFFICE.

GEORGE W. TUCKER, OF WATERVILLE, CONNECTICUT.

WARDROBE-HOOK.

SPECIFICATION forming part of Letters Patent No. 425,918, dated April 15, 1890.

Application filed January 3, 1890. Serial No. 335,787. (No model.)

To all whom it may concern:

Be it known that I, GEORGE W. TUCKER, a citizen of the United States, residing at Waterville, in the county of New Haven and State 5 of Connecticut, have invented certain new and useful Improvements in Wardrobe-Hooks; and I do hereby declare the following to be a full, clear, and exact description of the invention, such as will enable others skilled in 10 the art to which it appertains to make and use the same.

My invention relates to the construction of wardrobe-hooks, towel-racks, and similar articles, more especially a fine grade thereof, and 15 has for its object the production of an attractive and salable article, which may be produced at such an extremely low cost as to enable it to be placed upon the market at a price no greater than the present price of much 20 inferior goods.

With this end in view I have devised the novel construction of which the following description, in connection with the accompanying drawings, is a specification.

25 Figure 1 is a front elevation, Fig. 2 a side elevation, and Fig. 3 a back view, of one of my novel wardrobe-hooks; and Fig. 4 is a top plan view, the arms of the hook being removed and the central portion thereof in section.

30 As the invention is precisely the same when applied to the various articles of this general class, I have deemed it sufficient for the purposes of this application to show it applied to 35 wardrobe-hooks as I place them upon the market.

The entire device consists of three parts adapted to be formed by dies—to wit, a base-plate, a hook, and an attaching-plate.

40 1 denotes a piece of heavy wire bent to form a hook or pair of hooks, the central portion of said piece (denoted by 2) being left straight to provide a ready means of attachment to the base-plate, which is denoted by 3.

45 4 is an attaching-plate, the central portion 5 of which is curved to fit closely around the

central portion 2 of the piece of wire constituting the hooks, so as to hold the latter firmly in place, at the same time permitting the hooks to be swung when required, the 50 main portion of said plate lying close to the base-plate, and the ends thereof being curved around the edges and clamped down firmly upon the back of the base-plate, as clearly shown in Figs. 3 and 4, thereby holding the 55 parts firmly together.

The device is secured in place upon a strip or any suitable piece of wood-work by means of screws passing through holes 6, made through the attaching-plate and the base- 60 plate, as shown in Figs. 1 and 3.

It will be noticed that my improved construction is such as to enable the parts all to be formed mechanically and the assembling together of the parts to be performed by dies. 65 The hooks, including the central portion by which they are attached in place, are formed by a suitable machine from a coil of wire. The base-plate is struck up and formed complete at a single operation. The attaching- 70 plate is formed at a single operation, and the securing together of the parts is performed at a single operation, hand labor being entirely dispensed with in the manufacture.

Having thus described my invention, I 75 claim—

A pivoted wardrobe-hook consisting of a base-plate, a hook formed from wire and having a straight central portion, and an attaching-plate lying across the face of the base- 80 plate, the central portion of said attaching-plate being curved to inclose the straight portion of the hook and form a bearing therefor, and the ends being curved around the edges of the base-plate and pressed down upon the 85 back thereof.

In testimony whereof I affix my signature in presence of two witnesses.

GEORGE W. TUCKER.

Witnesses:

GEORGE S. PEARSON,
FRANK I. ROBERTS.
